[57] CLAIM

The ornamental design for a rotating condiment tray, as shown and described.

DESCRIPTION

FIG. 1 is a front elevational view of the rotating condiment tray of the present invention;

FIG. 2 is a cross sectional view along line 2—2 of FIG. 3 of the rotating condiment tray of FIG. 1.

FIG. 3 is a top plan view of the rotating condiment tray of FIG. 1; and,

FIG. 4 is a bottom plan view of the rotating condiment tray of FIG. 1.

The rear, left side and right side elevational views of the rotating condiment tray are identical to FIG. 1.
